UNITED STATES PATENT OFFICE.

JOHN S. CROXFORD, OF NEWPORT, MAINE.

GAME-TABLE.

SPECIFICATION forming part of Letters Patent No. 757,440, dated April 19, 1904.

Application filed August 19, 1903. Serial No. 170,066. (No model.)

To all whom it may concern:

Be it known that I, JOHN S. CROXFORD, a citizen of the United States, residing at Newport, in the county of Penobscot and State of Maine, have invented a new and useful Game-Table, of which the following is a specification.

My invention relates to that class of game-tables which consists of a frame and center or base board, said base-board being connected with the outer frame by canvas. In this canvas and arranged at regular intervals are pockets for receiving the balls with which the game is played.

My objects are, first, to provide a game-table where it is necessary for a ball to be thrown onto the center board and enter a pocket on its rebound to count the player anything, it being more desirable to strike the very center of the center board, thus requiring skill in the art of throwing accurately, at the same time with the required amount of force to cause the ball to stop where desired on its rebound; second, to provide a game-table where it is necessary for the player to assume a new position for each throw that he makes, thus making this a useful game-table; third, to provide a game-table that may be taken apart to occupy small space or may be set up quickly for playing, neither operation requiring the use of screw-driver, nail-hammer, or wrench, the table forming its own natural support and yet being firm and strong. I attain these objects by the arrangement illustrated in the accompanying drawings, in which—

Figure 1 is a general view of the game-table as it appears before putting on the drapery and ornamental ball-repositories. Fig. 2 is a sectional view of the base-board, showing the construction of the center pin and bell. Fig. 3 is a view of the lock-strap, by which the table is held in place. Fig. 4 is a view of one of the ornamental ball-repositories. Similar letters refer to similar parts throughout the several views.

The side pieces A A and the side arms B B constitute the framework of the table and in which are mortises y y, which receive the tenons on either end of the uprights t t.

Mounted upon the side arms B B is the base-board P, in which is the bell m.

Passing around the base-board P, being vertically slidable upon the same, is the steel band or lock-strap n, to which the lower edge of the canvas W W is secured by being passed around the lock-strap, lapped upon itself, and sewed together. At the several corners of the base-board are bands of iron o o, that are secured to the lock-strap n and pass around the side arms B B, fitting into slots d d.

In the upper edge of the canvas W W are eyelets e e for receiving the cord s s, and on the inside wall of the side pieces A A are hooks i i for receiving the cord s s; also for securing a drapery of any desired design. When the cord s s is passed through the eyelets e e and drawn up tightly, there is great strain on the frame and uprights, driving all the tenons into their mortises and bringing the straps o o into the slots d d; and on account of the peculiar arrangement of the uprights t t they form a natural brace and support to the entire framework.

In the canvas W W and arranged at regular intervals are pockets x x. These are made by securing a pocket-shaped net to an iron ring and securing the ring to the canvas. The pockets are of various sizes and numbered in their order by figures worked in the canvas. b b are pins passing through the side pieces A A.

In Fig. 2 the bell m is hung in a chamber in the base-board P. Beneath the bell and resting over the fulcrum a' is the rod v, which extends out under the center pin c. When the center pin c is struck with a ball, it comes in contact with the rod v, which, acting over the fulcrum a', strikes the bell.

Fig. 3 shows the design of the lock-strap n, that locks the side arms B B to the base.

Fig. 4 shows the design of the ornamental ball-repositories, which consist of the wire H, bent in such a manner that they may be placed on over the corners of the table or removed at will. Attached to this wire H is the net j for receiving the balls when not in use.

What I claim, and desire to secure by Letters Patent, is—

1. In a game-table of the class described the

combination of a rectangular frame and depressed center board, canvas connecting the same and network pockets of different sizes in said canvas.

5 2. In a game-table of the class described the combination with a frame and depressed center board, canvas connecting the same, and network pockets of different sizes in said canvas, of a bell *m* located in said depressed center board and, so arranged that when the center pin *c* is struck with a ball, the bell will ring, substantially as described.

15 3. In a game-table of the class described the combination with a frame and depressed center board, canvas connecting the same, and network pockets of different sizes in said canvas, said depressed center board containing the bell *m*, of tenoned uprights or supports, tenoned on both ends and fitting into 20 mortises in the frame, and center board, and so arranged that they form a natural support and brace-work for the entire framework, substantially as described.

4. In a game-table of the class described, the 25 combination with side arms, depressed center board, side pieces provided with hooks, and tenoned uprights connecting the same; of a canvas located between the same and provided with openings, network pockets of different 30 sizes connected to the margins of said open-

ings; a bell contained in the center board and provided with operating means; said canvas being secured to center board and provided with eyelets near its periphery, and a strengthening-cord passing through said eyelets and 35 over said hooks, substantially as described.

5. In a game-table of the class described, the combination with side arms having slots, depressed center board, side pieces provided with hooks, and tenoned uprights connecting the 40 same; of a canvas located between the same and provided with openings, network pockets of different sizes connected to the margins of said openings; a bell contained in the center board and provided with operating means; a 45 lock-strap passing around said center board, being vertically slidable upon the same and having loops passing around said side arms and fitting into slots in the same; said canvas being fastened to said lock-strap and provided 50 with eyelets near its periphery; and a strengthening-cord passing through said eyelets and over said hooks, substantially as described.

In testimony whereof I have signed my name in the presence of two subscribing witnesses. 55

JOHN S. CROXFORD.
